(74) Attorney, Agent, or Firm—Sterne, Kessler, Goldstein & Fox P.L.L.C.

(57) **CLAIM**

The ornamental design for an exercise device, as shown and described.

DESCRIPTION

FIG. 1 is a perspective view of an exercise device showing a new design; and,

FIG. 2 is side elevational view thereof. The opposite side being identical thereto.

The even broken line showing portions of an exercise device is environmental for illustrative purposes only and forms no part of the claimed design.

1 Claim, 2 Drawing Sheets
